(57) **CLAIM**

The ornamental design for a classic standard wall-mount shower head, as shown and described.

DESCRIPTION

FIG. 1 is a right-side perspective view of a classic standard wall-mount shower head showing our new design;

FIG. 2 is a front elevation view thereof;

FIG. 3 is a left side elevation view thereof, of which the right side elevation view is a mirror image;

FIG. 4 is a top plan view thereof;

FIG. 5 is a rear elevation view thereof; and,

FIG. 6 is a bottom plan view thereof.
